US0D1064495S

(12) **United States Design Patent** (10) **Patent No.:** **US D1,064,495 S**
(45) **Date of Patent:** **** Mar. 4, 2025**

(54) **HEATED GLOVE**

(71) Applicant: **SHENZHEN ZHIXIN CHUANGMENG TECHNOLOGY CO., LTD**, Shenzhen (CN)

(72) Inventor: **Yixia Liu**, Shenzhen (CN)

(73) Assignee: **SHENZHEN ZHIXIN CHUANGMENG TECHNOLOGY CO., LTD**, Shenzhen (CN)

(**) Term: **15 Years**

(21) Appl. No.: **29/893,709**

(22) Filed: **Jun. 1, 2023**

(51) LOC (15) Cl. **02-06**

(52) U.S. Cl. **D2/617**

(58) **Field of Classification Search**

USPC D2/617, 618, 619, 610, 614; D29/113, D29/115

CPC A41D 19/00; A41D 19/0024
See application file for complete search history.

(57) **CLAIM**

The ornamental design for a heated glove as shown and described.

DESCRIPTION

FIG. 1 is a perspective view of a heated glove showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the heated glove where the heated glove is in a configuration of use; and,

FIG. 10 is an enlarged view of portion 10 shown in FIG. 1. The thick evenly spaced broken lines in the drawings depict stitching and form no part of the claimed design. The thin evenly spaced broken lines immediately adjacent to the shaded areas depict the bounds of the claimed design, while all other thin evenly broken lines are directed to environment, and the thin evenly spaced broken lines form no part of the claimed design. The dot-dash broken lines represent boundaries of the enlarged portion and form no part of the claimed design.

1 Claim, 10 Drawing Sheets
